United States Patent Office.

HENRY H. HAYDEN, OF NEW YORK, N. Y., ASSIGNOR TO HOLMES, BOOTH,
AND HAYDEN, OF WATERBURY, CONNECTICUT.

Design No. 2,548, dated January 15, 1867.

DESIGN FOR THE HANDLE OF A FORK OR SPOON.

The Schedule referred to in these Letters Patent and making part of the same.

TO ALL WHOM IT MAY CONCERN:

Be it known that I, HENRY H. HAYDEN, of the city and State of New York, have invented or produced a new and original Design for the Handles of Forks and Spoons; and I do hereby declare the following to be a correct description of the same, reference being had to the annexed photograph, showing a fork and a spoon with my ornamental design upon the handles.

At the end of the handle is a shield of an oval shape with scroll work around it, as at *a*. The broad portion of the handle is ornamented with beaded corrugations at *b*. Near the centre of the handle, and also at the junction of the handle with the fork or spoon, are beaded and raised ovals surrounded with scrolls and leaves, as at *c* and *d*, and the shank or narrow portion of the handle is formed with ornaments of beaded work with semicircular ends, as seen at *e*.

What I claim, and desire to secure by Letters Patent, is—

The design of the shape and configuration of the ornaments for the handles of forks and spoons, as herein set forth.

In witness whereof I have hereunto set my signature this 15th day of November, A. D. 1866.

H. H. HAYDEN.

Witnesses:

E. V. B. DODD,
G. O. MONROE.
